CLAIM

The ornamental design for a remote control for electric blanket, as shown and described.

DESCRIPTION

FIG. 1 is a top, front, and left side perspective view of a remote control for electric blanket showing our new design; FIG. 2 is a front elevational view thereof; FIG. 3 is a rear elevational view thereof; FIG. 4 is a right side elevational view thereof; FIG. 5 is a left side elevational view thereof; FIG. 6 is a top plan view thereof; and, FIG. 7 is a bottom plan view thereof.

The broken-line showing of written indicia in the drawings is illustrative of environmental association matter only and forms no part of the claimed design.
